UNITED STATES PATENT OFFICE.

WILLIAM H. LA ROSAE AND RALPH W. BUZARD, OF BROOKVILLE,
INDIANA.

TOPICAL REMEDY.

SPECIFICATION forming part of Letters Patent No. 417,254, dated December 17, 1889.

Application filed March 21, 1889. Serial No. 304,202. (No specimens.)

To all whom it may concern:

Be it known that we, WILLIAM H. LA ROSAE and RALPH W. BUZARD, citizens of the United States, residing at Brookville, in the county of Franklin and State of Indiana, have invented a new and useful Anæsthetic Compound, of which the following is a specification.

The invention relates to an anæsthetic compound designed to be used in dental and other surgical operations; and it consists of the following ingredients in the proportions named: crystals of menthol, eight parts; tincture of cannabis indica, sixteen parts; tincture of gelsemium, two parts; tincture of veratrum viride, two parts; chloroform, one part; oil of sassafras, one part; sulphuric ether, one part; deodorized alcohol, sixty-three parts.

Place the alcohol in a suitable vessel, and after adding the menthol agitate until the latter is thoroughly dissolved. After standing for about ten minutes add the cannabis indica, gelsemium, and veratrum viride separately, thoroughly mixing each with the solution of cannabis indica before adding the next. After agitating vigorously for about fifteen minutes add the sulphuric ether and chloroform, and allow the mixture to stand for one - half hour. Then add the oil of sassafras and agitate slowly for fifteen minutes.

The menthol and cannabis indica are anæsthetics, serving to deaden the nerves and deprive them of feeling. The gelsemium and veratrum viride produce together a rigidity of the tissues and ligaments, the former serving to moderate the effect of the latter, as the latter alone would have too great an effect. The chloroform and sulphuric ether are used in this compound as febrifuges to prevent the fever which is liable to result from the operation and from the presence of decaying matter. The alcohol is used as a vehicle to enable the other ingredients to be thoroughly mingled, and the oil of sassafras

is used to give the compound a pleasant flavor.

The compound may be applied to the surface by means of a sponge, or it may be injected by means of a hypodermic syringe, according to the requirements of the case. The effect of the anæsthetic continues from twenty to thirty minutes.

The advantages of the compound are that no lasting effect is produced upon the patients, no unpleasant flavor is left in the mouth, and it may be applied to persons of all ages and temperaments without producing deleterious effects.

The compound herein described is designed merely as a local application, but may be used in some cases with great advantage as a hypodermic injection. It is adapted for use in surgical operations, more especially in dental operations, and the manner of using depends greatly upon the character of the case; but in ordinary cases may be briefly described as follows: Place upon a small sponge about five drops of the medicine and apply to the gums in the immediate locality of the teeth or to whatever portion of the body to be subjected to a subsequent operation. Hold the sponge in its place during a period of about two minutes, then remove, and, if desired, inject with a hypodermic needle. The dose of injections varies from three to eight drops, the maximum only being used when the dentine is extremely sensitive. In cleaning and filling teeth the hypodermic injection is not necessary unless the gums are very sore. The local application may be repeated as often as is found necessary in order that the gums may be maintained in an insensitive state.

When the medicine is applied to other mucous tissues, the dose in local application is from six to ten drops, and in hypodermic injections from six to twelve drops.

A surgeon after having familiarized himself with the results of the medicine, however, may regulate the dose in accordance

with his experience and experiments and to meet the requirements of his special case.

We claim—

The compound for the purpose named, consisting of menthol, tinctures of cannabis indica, gelsemium, and veratrum viride, chloroform, sulphuric ether, oil of sassafras, and alcohol, in substantially the proportions specified.

In testimony that we claim the foregoing as to our own we have hereto affixed our signatures in presence of two witnesses.

WILLIAM H. LA ROSAE.
RALPH W. BUZARD.

Witnesses:

GEORGE FRIES,
SAMUEL S. HARRELL.
